SAFETY BELT BUCKLE

Stanley J. Wisniewski, Chicago, Ill., assignor of twenty-five percent to Walter Wisniewski and Jeanette Wisniewski, Chicago, Ill.

Filed Apr. 22, 1963, Ser. No. 274,487

6 Claims. (Cl. 24—230)

This invention relates to belt buckles and more particularly to a novel and improved safety belt buckle.

Although there are very many different types of belt buckles in use today, I have found that there is no buckle which is simple in operation, effective in use and which is inexpensive to manufacture so as to be available to the public at a relatively low price. Most of the belt buckles which feature a quick-release utilize an overcenter cam structure which presses a belt inserted therebeneath against the body portion of the buckle. The locking action is not positive and the belt is continuously subjected to abrasion and wear.

It is a general object of my invention to provide a novel belt buckle which is of rugged and durable construction in which the operating parts are mutually shielding to prevent their destruction or malfunctioning.

A further object of the invention is to provide a novel belt buckle which incorporates an ingenious locking mechanism for a metal tongue on the free end of the associated belt.

The invention comprehends the provision of a belt buckle which comprises a body portion secured to one end of a belt, and which receives a tongue which may be at the other end of the belt, the body portion of the buckle providing a tongue way which admits one end of the tongue therein, the body portion also mounting locking means which cooperates with complementary locking means on the tongue and wherein the parts function to releasably lock with each other and wedge into releasable locked position.

More specifically the invention provides a buckle having a spring-loaded abutment against which the end of the tongue bears, the tongue having an end portion of novel form which comprises a transverse aperture admitting a spring-loaded latch therein and reacting against the latch to engage the same with portions of the buckle to hold the parts in tight engagement with each other.

Another object is to provide a novel buckle with a spring-loaded self-ejecting tongue such that upon depressing the buckle latch, the tongue is forcibly ejected from the buckle to release it.

These and other objects and advantages inherent in and encompassed by the invention will become more readily apparent from the specifications and the drawings, wherein:

FIGURE 1 is a plan view of the novel buckle and tongue partially broken away to illustrate the interior;

FIGURE 2 is a side elevational view of the novel buckle and tongue;

FIGURE 3 is a longitudinal sectional view taken essentially on line 3—3 of FIGURE 1 showing the parts in locked position;

FIGURE 4 is a side elevational view partly in section of the novel buckle and tongue showing the parts in released position;

FIGURE 5 is a perspective view of the base;

FIGURE 6 is a perspective view of the tongue; and

FIGURE 7 is a perspective view of the latch partly broken away.

Description of the invention

Describing the invention in detail and having particular reference to the drawings, there is shown a belt buckle

2

2 which has a base portion 3 and a holder or latching portion 4, the buckle cooperating with a tongue 5.

The base portion 3 comprises a bottom wall 6 which is flanked by integral upstanding flanges 7, 7, which together with the base form an enclosure for a spring loaded ejector-abutment assembly 8.

The abutment assembly comprises a transverse guiding and seating bar 9 which may be integral with the bottom wall 6 of the base portion and has its ends integrated with the flanges 7, 7. The bar 9 is provided with a central aperture 10 which admits a guide and mounting rod 12 which extends through a compression spring 14. The spring 14 which is a resilient element, reacts at one end against the forward side 15 of the reaction bar or member 9 and at the other end against the back side 15' of an abutment block 16. The block 16 is preferably of rectangular shape and has its back side 15' connected centrally thereto to the rod 12. The side or lateral edges 19 of the block are guided between the interior sides 20 of the flanges 7 and the block is movable reciprocally lengthwise along its lower edge 22 on the bottom wall 6 toward and away from the free or front portion 23 of the buckle body portion 3.

The front end portion 23 provides a forwardly open tongue-receiving slot or way 25 which admits the free end portion 26 of the tongue which is angled upwardly from the base wall 6 and has a diagonal forward marginal edge 27 engaging the forward vertical face 28 of the abutment block 16. The tongue end portion 26 has a top side 30 which engages the underside 31 of the rear locking ledge 32 which spans the space between the upstanding flanges 7, 7 and is connected thereto along their upper edges 33 at the forward end portion of the buckle behind the locking hook or catch 34 of the holder or latch 4.

The catch 34 extends through a slot or aperture 35 formed between ledge 32 and the coplanar ledge 36 which is also formed integral with flanges 7 adjacent to the upper edges 33 thereof.

The catch 34 has a lower end portion 37 which is angled inwardly from the front end of the buckle and in the locked position projects through the eye or opening or slot 38 in the forward end portion 26 of the tongue. The lower end portion 37 has a lower edge 40 which engages the top side 41 of the bottom wall 6 of the base.

The block 16 urges the tongue outwardly and engages the convex forward side 43 of the hook 34 with the rear edge of the crest 44 of the forward ledge 36. The engagement occurs below the crest of curvature shown at 44' so that upon engagement of the forward margin 45 of the slot 38 in the tongue with the curved back edge 46 of the catch 34, which slopes upwardly and outwardly, the hook is caused to wedge downwardly against the tongue as well as the outer ledge 32, against its back edge 44.

The latch is accommodated pivotal movement as well as limited longitudinal movement through a lost motion connection generally designated 48 which comprises a pintle 50 secured in coaxial apertures 51 in the flanges 7, the pintle passing through coaxial longitudinally elongated slots 52 in the side flanges 53, 53 of the latch, said flanges 53 overlapping the flange 7, 7 and disposed generally parallel thereto outwardly thereof. The lower edges 54, of the flanges 53 are sloped at 55 and merge into the lateral margins 56 of the catch adjacent to its upper or outer end 57. The flanges 53 also merge along their outer or upper edges with the top or outer wall 58 of the latch, said wall 58 merging at its forward end 59 with the outer end 57 of the catch and at its rear end with a transverse rear wall 60 which merges with the rear ends of the side flanges 53.

70

The rear wall 60 has a lower edge 61 spaced upwardly from the generally straight edge portions 54 of the side flanges 53 to accommodate pivotal movement of the latch at its rear end portion 62 toward the base as this portion is depressed by the user against the compression of the spring 63 which is interposed between the base wall 6 and the bottom side 64 of the top wall 58.

The spring or resilient element 63 is mounted on a stud 65 on the wall 6 and is held in place on wall 58 by a projection 66 formed on the inner side 64 of the top wall 58 of the latch.

It will be noted that the rear portions 66, 66 of the top edges of the flanges 7 are angled from adjacent to the pintle to the rear edge 68 of the bottom or base wall 6 to accommodate adequate inward movement of the rear portions 62 of the latch while the forward portion 57 of the latch is caused to move outwardly withdrawing the catch 34 from the tongue slot 35 and clearing the way 25 and the inner end portion 26 of the tongue so that it is forcibly ejected from the buckle way 25 to release position. It will be noted that as the latch is depressed at its rear end 62 it moves bodily slightly rearwardly as permitted by the slots 48 which are elongated transversely of the catch 34. Thus the crest 44' of the curved forward side 43 of the catch 34 passes through slot 35 which is dimensioned of sufficient width to accommodate the curved catch portion 34.

Upon the tongue being withdrawn from the buckle the forward side 28 of the block 16 engages with the back edge 72 of the rear ledge 32 to limit outward travel of the block.

The tongue has a slot at 74 to which one end of a belt 75 is connected. The other end of the belt or another belt length 75a is connected to the buckle through slot 76 to the base wall 6.

It will be understood that a preferred embodiment of the invention has been disclosed and that various other forms of the invention will become readily apparent within the scope of the appended claims which they are intended to cover.

What is claimed is:

1. In a belt buckle, a base member, a latch member having a lost-motion pivotal connection with the base member comprising slot means on one of said members elongated lengthwise of the buckle and pin means on the other member extending through the slot means and accommodating relative movement between the members lengthwise of the buckle, a catch on the latch member movable toward the base member to locking position and away from the base member to open position, a tongue extending into the base member from one end thereof and having an opening receiving the catch member therein, biasing means in the base member engageable with the tongue urging the same in an outward direction from the base member against said catch member and moving said catch member with the tongue lengthwise of the buckle within the limit of the lost-motion, and means on the base member for releasably holding said catch member in locking position disposed outwardly of the catch member and engageable thereby pursuant to the action of the biasing means as aforesaid.

2. A buckle according to claim 1 and said catch member having a side facing said biasing means, and said tongue having a portion between said biasing means and said side of the catch member and having wedging engagement therewith urging the catch member to locking position.

3. In a self-ejecting buckle-tongue combination, a buckle having a longitudinal way, a tongue extending into said way from one end thereof, a spring-loaded abutment in said way opposing inward movement of the tongue into said way, and a catch pivoted on the base and extend-

ing through an aperture in the tongue restraining ejection of the tongue by said abutment, said catch pivotal to a position withdrawing the same from the aperture in the tongue whereupon said tongue is ejected from the buckle, and a pair of ledges on the base defining a slot therebetween admitting said catch therethrough, and said catch and base being relatively movable longitudinally and said catch engaging one of said ledges under the influence of the abutment urging the tongue against said catch.

4. In a self-ejecting buckle-tongue combination, a buckle having a longitudinal way, a tongue extending into said way from one end thereof, a spring-loaded abutment in said way opposing inward movement of the tongue into said way, and a catch pivoted on the base and extending through an aperture in the tongue restraining ejection of the tongue by said abutment, said catch pivotal to a position withdrawing the same from the aperture in the tongue whereupon said tongue is ejected from the buckle, and a pair of ledges on the base defining a slot therebetween admitting said catch therethrough, and said catch and base being relatively movable longitudinally and said catch engaging one of said ledges under the influence of the abutment urging the tongue against said catch and said catch having means thereon engageable under said one ledge for releasably holding the catch against accidental displacement for locking position.

5. In a buckle, a base having a bottom wall and a pair of upstanding laterally spaced flanges, defining a way therebetween, said buckle having a forward end portion, a pair of ledges including an inner and an outer ledge spaced lengthwise of the buckle and interconnecting said flanges adjacent to said forward edge and defining a catch-receiving aperture therebetween transverse to said bottom wall, a transverse bar in said way disposed intermediate the ends of the buckle, an abutment member in said way between the forward end of the buckle and said bar, spring means interposed between said bar and said abutment urging the latter toward the forward end of the buckle, a latch having a wall generally parallel to the bottom wall and a pair of lateral flanges overlapping respective flanges of the base, a pin extending through all of the flanges and disposed generally parallel to said walls, certain of said flanges having slots elongated generally parallel to said walls, a catch on one end of the latch connected to the wall and flanges thereof and projecting through the slot between said ledges, said catch having a convex outer surface with its crest of curvature between said outer ledge and said bottom wall of the buckle in locked position of the catch and said outer surface engageable with an opposing edge of the outer ledge.

6. In a buckle according to claim 5 and said catch having a back surface transverse to said bottom wall and opposing said abutment, and a tongue having a portion between the abutment, the back surface and in wedge engagement therewith and urged against said inner ledge.
